UNITED STATES PATENT OFFICE.

EDGAR A. CUNNINGHAM AND HARRY HOMAD, OF MALLORY, WEST VIRGINIA.

MINING-CAR COUPLING.

Application filed June 12, 1923. Serial No. 644,879.

To all whom it may concern:

Be it known that we, EDGAR A. CUNNINGHAM and HARRY HOMAD, citizens of the United States, residing at Mallory, in the county of Logan and State of West Virginia, have invented certain new and useful Improvements in Mining-Car Couplings, of which the following is a specification.

This invention relates to certain new and useful improvements in car couplings and more particularly to that class known as mining car coupling.

The present invention has for its objects among others to provide a simple, cheap, yet efficient and reliable mining car coupling which is automatic in the action of coupling but which will effectually and reliably hold the two cars in coupled relation, allowing sufficient relative movement of the two cars while in motion, and to permit them to readily round a curve without separation.

Other objects and advantages of the invention will hereinafter appear and the novel features thereof will be particularly pointed out in the appended claims.

The invention, in its preferred form, is clearly illustrated in the accompanying drawing, which, with the numerals of reference marked thereon, form a part of this specification, and in which

Figure 1 is a side elevation showing portions of adjacent ends of two mining cars equipped with our improved coupling.

Figure 2 is a substantially central vertical longitudinal section through the coupling.

Figure 3 is a vertical transverse section on the line 3—3 of Figure 1, looking in the direction of the arrows.

Figure 4 is a perspective view of the coupling bar or link removed.

Like numerals of reference indicate like parts throughout the different views.

Referring to the drawings, 1, 1 designate the adjacent ends of two mining cars of known or any approved form of construction except as hereinafter specified. 2, 2 are the wheels thereof and 3, 3 the end portions of the platform of the cars, the same being provided with bumpers 4, as usual.

As the coupling members on each car are similar in all respects, the description of one will suffice for both.

5 is a housing which may or may not have a side opening, as shown at 6, for ac-

cess to the parts of the coupler, and this opening may or may not be closed in any suitable manner. The housing 5 terminates in the flaring or funnel-shaped mouth 7, as seen best in Figures 1 and 2.

In the face of the housing there is a channel 8 formed by the parallel side members 9 and in this channel is designed to work the locking member 10 which is pivotally mounted upon a transverse rod or pin 11 mounted in the side portions of the housing, see Figure 2, this locking member having an offset portion 12 providing a flat face 13 which is adapted to engage a shoulder 14 formed at one end of the longitudinal recess 15 in the under side of the coupling bar or link 16, as seen in Figures 2 and 4. This coupling bar or link is provided with such recess 15 near each end, as clearly shown in said Figures 2 and 4.

17 is an unlocking lever secured to the shaft 11 adapted to be operated in any suitable way, either from the ground or by a person on the car. It is shown as provided with a counterweight 18 at one end to normally keep the locking lever in locked position, which is that indicated by full lines in Figure 2.

The locking member 12 may be secured to its shaft 11 in any suitable manner, but in the present instance we have chosen to show it as secured by a screw or the like 19, see Figure 2, and in order to provide ready access to such screw we provide the lower wall of the flaring mouth with an opening 20, as seen in Figure 2.

In order to guide the coupling bar or link in position and also to hold it against undue movements and yet resiliently engage the same, we provide springs 21, in the present instance shown as three in number, although more or less may be employed if desired, these springs being secured at one end by any suitable means, as the screws or the like 22, to the inner walls of the housing and the other ends being free and curved, as seen in Figure 2, and adapted to embrace the inner end of the coupling bar or link upon three sides thereof.

The coupling bar or link 16 is shown as provided upon its upper face with a lug 23, one near each end, which is adapted to be received in the notch or recess 24 in the mouth of the housing, as seen clearly in Figures 2 and 3.

With the parts constructed and arranged

substantially as hereinbefore described, the operation should be readily understood, and, briefly stated, is as follows:—the coupling bar or link will normally be locked in position within one of the coupling heads ready for coupling with the adjacent part. As the cars approach, the free end of the coupling bar or link entering the flaring mouth of the car to be coupled will be guided into proper position regardless of whether the two cars are in longitudinal alinement or not; the locking member serving to hold the engaged end of the coupling bar or link against separation regardless of the movements of the coupling bar or link. As the free end of the coupling bar or link enters the flared mouth of the coupler of the car to be coupled, it will be guided into place, and its under surface riding over the pivoted locking member will move the same on its pivot until the notch or recess in the under side of the bar is in position to receive the locking member, when the latter falls by gravity into such position that its vertical face will engage the end wall of the recess when the weighted end of the lever drops and the cars are coupled. The coupling is such that the cars cannot become separated under any condition until the attendant moves the weighted lever so as to throw the coupling member from its full

line to its dotted line position, when the cars can be separated.

Modifications in detail may be resorted to without departing from the spirit of the invention or sacrificing any of its advantages.

What is claimed as new is:—

1. In a mining car coupling, a housing member having a flaring mouth, a weighted locking member pivotally mounted within said mouth and having an offset portion with square shoulder, a coupling bar with longitudinal recess in its under face with a shoulder, against which said flat shoulder engages, and a spring extended inwardly in said member and bearing on the inner end of the coupling bar.

2. In a mining car coupling, a housing member having a flaring mouth, and having an offset portion with flat face, a coupling bar with longitudinal recess in its under face with a shoulder against which said flat face engages, a spring extended inwardly in said member and bearing on the inner end of the coupling bar, the top wall of said housing member having a notch in its under side and the coupling bar having an upwardly-extending lug engaged in said notch.

In testimony whereof we affix our signatures.

EDGAR A. CUNNINGHAM,
HARRY HOMAD.
